UNITED STATES PATENT OFFICE.

ANDREW KERSCHGENS, OF CHARLEROI, PENNSYLVANIA, ADMINISTRATOR
OF JOSEPH KERSCHGENS, DECEASED.

COKE-OVEN.

No. 850,939.

Specification of Letters Patent.

Patented April 23, 1907.

Application filed September 8, 1906. Serial No. 333,852.

To all whom it may concern:

Be it known that JOSEPH KERSCHGENS, deceased, formerly a citizen of the United States, and resident of Charleroi, in the county 5 of Washington and State of Pennsylvania, did invent a new and useful Coke-Oven, of which the following is a specification.

This invention relates to coke-ovens; and its object is to provide means whereby the 10 gaseous products of the coal may be conducted from a plurality of ovens through a common conduit, from which they can be removed for heating and other purposes.

With the above and other objects in view 15 the invention consists of certain novel features of construction and combinations of parts, which will be hereinafter more fully described, and pointed out in the claims.

In the accompanying drawings is shown 20 the preferred form of the invention.

In said drawings, Figure 1 is a view, partly in elevation and partly in section, of the ovens; and Fig. 2 is a section from front to rear thereof.

25 Referring to the figures by characters of reference, 1 is a housing of brickwork, in which are formed a number of similar parallel ovens 2, which extend through the brickwork and are provided with doors 3 at the two ends thereof. Inlet-openings 4 open into the tops of the ovens and have closures 5 at their upper ends. A track 6 extends along the brickwork close to these openings, and cars containing coal for the ovens are 30 adapted to be moved therewith into position to discharge the coal into any one of the openings. Outlet-ports 7 are formed in the walls of the ovens and communicate with flues 8, which extend downward within said 35 walls and under the bottoms of the ovens and then open into discharge-conduits 9, one of these conduits being provided for each oven. A main or collecting conduit 10 is arranged below and in front of the ovens, and the discharge-conduits all open into it. Each of 40 the discharge-conduits 9 has a door 11, mounted in guide and supporting cleats 12, and these doors are adapted to be raised into recesses 13, formed in the top of the conduit 45 10. A track 14 extends over the conduit 10, and a truck 15 is adapted to travel thereon, said truck carrying a windlass 16, having a cable or chain 17 wound thereon and adapted to be placed in engagement with any one of 50 the closures 11. A stack 18 extends from 55

one end of the conduit 10 and is provided with a suitable damper 19 for regulating the flow of gases through the stack. A gas-outlet 20 is preferably located below the stack and within the conduit 10 for conducting the 60 generated gas to points where it may be used for various purposes.

It is thought that the operation of the ovens will be thoroughly understood in view of the foregoing description. Coal is discharged into each of the ovens 2 and fired in the usual manner, the damper 19 being left open for a predetermined period, so as to permit the products of combustion to pass outward from the ovens through flues 8 and conduits 9 and thence upward to stack 18. Air is of course admitted to the ovens in any preferred manner. After this combustion has been continued for a proper period the admission of air to the ovens is stopped and the 70 damper 19 is closed, whereupon the coking in the ovens will continue. The gas generated by heating the coal flows downward through the flues 8 and into the discharge-conduits 9, which may be opened by moving the windlass 16 above the closures 11 and raising them therewith and then locking them in any preferred manner. The gas generated in all of the ovens will thus be directed into a common outlet 20, and a considerable saving in 75 the cost of the ovens will thus be made. Should it be desired to empty or fill any one of the ovens, this can be done without the necessity of closing down the remaining ovens, as it is merely necessary to close the discharge-conduit of the oven to be shut down. Moreover, the close proximity of the other 80 furnaces will prevent the oven from cooling to any great extent while the same is being emptied or filled. It is of course understood 85 that the walls of the ovens will retain the heat to a sufficient degree to fire all subsequent charges of coal which may be placed within the ovens after the removal of hot coke therefrom.

The preferred form of the invention has been set forth in the foregoing description; but the inventor did not limit himself thereto, as he was aware that modifications may be made therein without departing from the spirit or 90 sacrificing the advantages thereof, and he therefore reserved the right to make such changes as fairly fall within the scope of the 95 claims.

What is claimed is—

1. The combination with a plurality of ovens, each oven having a flue in the bottom thereof and independent flues in its walls opening into the bottom flue; of a collecting-
5 conduit disposed below the ovens, a stack communicating with said conduit, a discharge-conduit extending from the bottom flue of each oven and into the collecting-conduit, a vertically-movable valve for closing communication between each discharge and the collecting conduits, a track in front of the ovens and above the collecting-conduit, and means movable upon the track for actuating the valves.
10 2. The combination with a plurality of ovens, each oven having a flue in the bottom thereof and independent flues in its walls opening into the bottom flue; of a collecting-conduit disposed below the ovens, a stack at one end of the collecting-conduit, means for

closing communication between the stack and conduit, a valved gas-outlet within the collecting-conduit, a discharge-conduit extending from the bottom flue of each oven to the collecting-conduit, a vertically-movable valve for closing communication between each discharge and the collecting conduits, a track in front of the ovens and above the collecting-conduit, and means upon the track for actuating any one of the valves. 25
30

In testimony whereof I have signed my name to this specification in the presence of two witnesses.

ANDREW KERSCHGENS,
Administrator of the estate of Joseph Kerschgens.
